DRIVE MECHANISM FOR SHAKER CONVEYERS

Glenn W. Packer, Chicago, Ill., assignor to Goodman Manufacturing Company, Chicago, Ill., a corporation of Illinois

Application September 27, 1934, Serial No. 745,655
Renewed September 4, 1936

16 Claims. (Cl. 198—220)

This invention relates to improvements in drive mechanisms for shaker conveyers of the type utilized for conveying loose material, such as coal, and more particularly to drives of the type 5 in which the violence of conveying action may be varied, or the direction of the action may be reversed under the control of the operator.

More specifically, the present invention is directed to improvements in construction of the 10 type of drive mechanism disclosed in the application of William W. Sloane, Serial No. 712,969, filed February 26, 1934, and has for its object to provide a simplified construction which is capable of producing more accurate control in 15 variations of the conveying action and is more economical to manufacture.

Other objects of my invention will appear from time to time as the following description proceeds.

My invention may best be understood with 20 reference to the accompanying drawings, in which:

Figure 1 is a top plan view showing a device embodying my invention operatively connected with a section of conveyor troughing;

Figure 2 is an enlarged plan view of the mechanism with a portion of the gear cover removed and with parts broken away and shown in horizontal section to show the details thereof;

Figure 3 is a sectional view taken substantially 30 on line 3—3 of Figure 2;

Figure 4 is an end view of the gear casing, drawn to a smaller scale than Figure 3, but showing in dotted lines the arrangement of the mechanism for reversing the direction of movement of material along the pan line;

Figure 5 is a diagram, or graph, showing certain hypothetical velocity curves of shaker motions attainable by the shaker mechanism; and

Figure 6 is a detail section of the worm gear locking mechanism.

Referring now to the drawings which illustrate one embodiment of my invention, a shaker drive mechanism indicated generally by numeral 10, is mounted on a base plate 11 adapted to be 45 held in position on the mine bottom in the usual manner, as by a plurality of jacks (not shown).

The general arrangement of the drive mechanism, and the details of the planetary gear reduction mechanism utilized therein are the same as shown and described in the aforementioned application of William W. Sloane, but as all of said parts cooperate to produce the desired variations in shaking motion, said parts will be briefly described.

A casing 16 having cover plate 17 is secured to the horizontal legs of a pair of angles 14, 14 suitably secured to the base plate 11, as by welding. One end of said casing is enclosed by end plate 18 of a motor 19, of standard construction 5 having an armature shaft 20.

The armature shaft 20 has a pinion 21 keyed thereto which acts as the sun pinion for a planetary gear reduction device, indicated generally at 28 (see Figure 2).

The pinion 21 meshes with and drives planetary gears 22, 22 carried on parallel-spaced shafts 23, 23 which shafts are journaled adjacent their ends in a cage 24. Said cage is provided with a hub 25 keyed to an inner end of a shaft 26 15 and held in fixed relation with respect thereto by means of a suitable nut and washer, indicated by reference character 27. Said shaft is journaled adjacent the hub of said cage in a suitable anti-friction bearing member 29 carried in a suitable bearing support means, herein shown as being formed integral with the casing 16. A suitable anti-friction bearing member 30 carried in the outer end of said casing and held therein by a removable end plate 31 forms a 20 bearing for the opposite end of said shaft.

Planetary pinions 32, 32 are keyed on the shafts 23, 23 and spaced from the planetary gears 22, 22 and mesh with an internal ring gear 33. Said internal ring gear serves as a reaction member 30

for the planetary geared reduction device and its outer periphery and side adjacent the motor 19 abuts a shouldered portion of a rotatable support member 35, which support member extends over the planetary gears 22, 22 and is 35 journaled on a hub 36 formed integral with the end plate 18 of the motor 19. A spider 37 abuts the opposite face of said internal gear and is journaled on its hub in a suitable bearing member 38 carried on a shoulder 39 formed on a portion of the outer side of the support member 40 for the bearing 29. The support member 35 and spider 37 are secured to each other, and to the internal ring gear 33 by means of suitable nuts and bolts 40, 40 so that all of said 45 last-named parts may rotate as a unit.

It will be apparent that rotation of the sun pinion 21 will rotate the cage 24 within the internal gear 33 when said internal gear is held 50 from movement. When the internal gear 33 is free to rotate in the direction of rotation of the cage 24, the speed of rotation of said cage will be increased, but when the internal gear 33 is rotated in an opposite direction, the speed of rotation of said cage will be decreased.

55

The outer end of the shaft 26 extends beyond the bearing 30 and is provided with a crank 41, herein shown as being formed integral with said shaft. Said crank has a pusher rod or pitman 43 journaled thereon by means of a suitable bearing member 44. The free end of said pusher rod is pivotally connected to a connecting member 45, secured to and depending from a conveyer trough 46 for reciprocably moving said conveyer trough upon rotation of said crank.

Referring now in particular to the mechanism for changing the rate of acceleration of the crank 41 which mechanism forms the subject matter of the present invention, the same comprises a novel arrangement for rocking the internal gear 33 alternately in opposite directions during each revolution of said crank. Said mechanism, as herein shown, includes a crank 47, formed integrally with the shaft 26 intermediate the bearings 29 and 30. Said crank is so disposed with respect to the crank 41 that it is 90° out of phase therewith, in a manner similar to that described in the foregoing application of W. W. Sloane. In my improved construction, 25 the crank 47 has bearing in an anti-friction bearing 49 carried by a block 50. Said block is part of a Scotch yoke in which said block is arranged for horizontal sliding movement between upper and lower guide members 51a, 51b of a frame or 30 yoke 52. Said frame, in turn, is guided for vertical movement by means of upright flanges 53, 53 slidable in grooves 54, 54 formed between outer bearing strips 55, 55 engaging the end wall of casing 16 and inner bearing strips 56, 56 secured 35 to offset portions 57, 57 of the casing by detachable plates 58, 58 suitably secured, as by cap screws 59, 59.

The frame 52 is also provided with a hollow annular extension 60 surrounding the crank 47. 40 A link 61 has its larger end rotatably mounted on said annular extension, and its smaller end pivotally connected to an intermediate point of a lever 69 by means of a pin 74.

The lever 69 is pivoted at one end to an 45 inwardly extending projection 71 of a worm gear ring 67 by a pin 72. Said worm gear ring is mounted within the casing 16 for rotatable movement with respect thereto, and its general arrangement and function is similar to that of 50 the worm gearing, previously employed in drive mechanisms of the same type; namely, to change the angular position of the lever 69, resulting in variations in violence of the shaking action, and also by suitable adjustment, as will presently appear, to reverse the effective direction of shaking movement.

In the improved form shown, the gear ring 67 abuts a shouldered portion 62 formed on the lower portion of casing 16, and a retaining ring 63 60 engages the opposite side of said ring, as shown in Figure 2.

A worm 67a, herein shown as being formed integral with a shaft 64, meshes with the worm gear ring 67. Said shaft has bearing at its 65 upper and lower ends in a housing 65 forming part of the casing 16 and is manually controllable by a hand wheel 66.

The outer end of the lever 69 is connected through a link 79 to a projection 81 by a pin 82. 70 Said projection extends outwardly from the spider 37 forming the reaction member of the planetary gear reduction device, previously described.

It will now be apparent that upon rotation of the shaft 26, the crank 47 will simultaneously 75 reciprocate the block 50 laterally in the frame

52 while said frame will be reciprocated in a vertical direction. The vertical component of rotation will be imparted from the frame 52 through the link 61 to the lever 69, provided said lever is properly positioned with respect to 5 said frame. Rocking movement of the lever 69 will rock the internal gear 33 in opposite directions during each revolution of the shaft 26 in the usual manner, so as to vary the acceleration and deceleration of the trough with respect to a 10 normal velocity curve, represented by the sine curve A of Figure 6, so as to assume an acceleration curve similar to that indicated by curve B of Figure 6, in which the trough will be given the desired shaking action, so as to progress material therewith in one direction. The greater the arc of movement of the internal gear 33 during each revolution of crank 41, the steeper will be the line, shown hypothetically by curve B of Figure 6, indicating the deceleration of the forward 20 stroke of the trough, resulting in an increase in material travel.

Referring to Figures 3 and 4, it will be observed that this difference in effective arc of rocking movement of the internal gear 33 may be controlled by rotation of the worm gear 67, through manipulation of the hand wheel 66. Rotation of the worm gear in a clockwise direction from the position shown in Figure 3 will result in a gradual decrease in movement of the lever 69 and internal gear 33 until a point is reached (when the pin 74 is approximately in a plane midway of the horizontal guide members 51a, 51b) where there will be no appreciable movement of said internal gear. The velocity curve of the trough 46 will then be 35 a sine curve and no movement of material will result, as has hereinbefore been explained.

Further movement of the worm gear 67 in a clockwise direction from a position where there is no appreciable movement of the internal gear 40 33, causes said internal gear to be rocked in an opposite direction and the peak of the acceleration curve occurs in the first 90° of the cycle of rotation of crank 41. Thus, in the position of the parts shown in dotted lines in Figure 4, the direction of movement of material will be reversed with respect to the position shown in Figure 3, since the velocity curve is then substantially as indicated at C in Figure 6, in which the acceleration and deceleration peaks are now on the opposite 50 sides of the peaks of the sine curve A from curve B.

As a further feature of my improved construction, I provide a novel locking means for restraining the worm gear ring 67 from rotation. 55 In the form shown, a semi-circular shoe 75 is fitted over the upper half of said worm, said shoe having depending flanges 76, 76, as clearly shown in Figure 6. The opposite ends of said shoe are provided with upright extensions 77, 77 which 60 fit in vertical sliding engagement between the side walls of the casing 16, as shown in Figure 3. Said shoe is adjusted to provide a braking or clamping action relative to said gear ring by means of a pair of set screws 78, 78 threaded 65 through the cover plate 17 and having extensions 80, 80 rotatably seated in the extensions 77, 77.

The advantages of my improved construction will now be more readily apparent to those skilled in the art. The parts controlling rocking movement of the reaction member 33 are simpler, less expensive, and more durable than those previously employed for this purpose. Moreover, my improved mechanism is especially designed to utilize, by selection, the vertical component only of ro- 75

tation of the crank arm 47. By applying this component directly to the rocking lever 69 in its various positions of adjustment, more uniform variations in acceleration and deceleration curves 5 are attainable, and the effectiveness of the drive may therefore be maintained substantially at maximum efficiency, even though the violence of shaking action may be varied widely, or reversed, as above described.

10 While I have herein shown and described one form in which my invention may be embodied, it will be understood that the construction and arrangement of the various parts may be changed or altered without departing from the spirit or 15 scope thereof. Furthermore, I do not wish to be construed as limiting myself to the precise construction illustrated, excepting as it may be limited in the appended claims.

I claim as my invention:

20 1. In a shaker conveyer drive, a driving shaft, a driven shaft having a crank thereon, drive gearing for rotating said crank with a predetermined variable angular velocity during each revolution thereof including an orbitally movable pinion, a 25 reaction member movable in opposite directions during each revolution of said crank meshed with said pinion, and means for reciprocably moving said reaction member in timed relation with said crank including a yoke mounted for translational movement in one plane, a member guided in said yoke for slidable movement in a plane disposed transversely to the plane of movement of said yoke, means for reciprocably moving said member in said yoke in one plane and simultaneously moving said yoke in a transverse plane, 30 and an operative connection between said yoke and reaction member.

2. A shaker conveyer drive in accordance with claim 1, in which the member is mounted on 40 said driven shaft eccentric of the center thereof.

3. A shaker conveyer drive in accordance with claim 1, in which the connection between the yoke and the reaction member includes a lever arm, and means for shifting the pivotal axis of said 45 lever arm in such a manner as to reverse the order of acceleration and deceleration of said driven crank without reversing its direction of rotation.

4. A shaker conveyer drive in accordance with claim 1, in which the connection between the 50 yoke and the reaction member includes an annular projection encircling said driven shaft, a link journaled thereon, and a lever arm fulcrumed adjacent one of its ends, said lever arm being connected to said reaction member adjacent its 55 opposite end, and to said link intermediate its ends.

5. A shaker conveyer drive in accordance with claim 1, in which the connection between the yoke and the reaction member includes a lever 60 arm, and means for shifting the pivotal axis of said lever arm in such a manner as to reverse the order of acceleration and deceleration of said driven crank without reversing its direction of rotation, and in which the pivotal axis of said 65 lever arm is adjustable about an axis concentric with the axis of said reaction member.

6. A shaker conveyer drive in accordance with claim 1, in which the connection between the yoke and the reaction member includes an annular projection encircling said driven shaft, a link 70 journaled thereon, and a lever arm fulcrumed adjacent one of its ends to an adjustable fulcrum member and connected to said reaction member adjacent its opposite end and said link intermediate its ends, and in which means are provided 75

for shifting said fulcrum member in such a manner as to reverse the order of acceleration and deceleration of said driven crank without reversing its direction of rotation.

7. A shaker conveyer drive in accordance with 5 claim 1, in which the connection between the yoke and the reaction member includes an annular projection encircling said driven shaft, a link journaled thereon, and a lever arm fulcrumed adjacent one of its ends to an adjustable fulcrum member and connected to said reaction member adjacent its opposite end and said link intermediate its ends, in which said adjustable fulcrum member includes a gear movable about any axis concentric with the axis of said reaction member, and in which means are provided for rotating said gear and other means are provided for locking said gear in a fixed position so as to reverse the order of acceleration and deceleration of said driven crank without reversing its direction of rotation.

8. In a shaker conveyer drive, a driving shaft, a driven shaft having a crank thereon, planetary drive gearing for rotating said crank with alternating acceleration and deceleration during each 25 revolution thereof, including a reaction member movable in opposite directions, means for shifting said reaction member in timed relation with said crank including a slidably mounted Scotch yoke guided for reciprocable movement and having an eccentric slidably movable transversely thereof and reciprocably driven in timed relation to said crank, and a connection between said yoke and said reaction member.

9. A shaker conveyer drive in accordance with 35 claim 8, in which the eccentric is mounted on said driven shaft and extends through said yoke.

10. A shaker conveyer drive in accordance with claim 8, in which the connection between the yoke and the reaction member includes a lever 40 arm, and means for shifting the pivotal axis of said lever arm in such a manner as to reverse the order of acceleration and deceleration of said driven crank without reversing its direction of rotation.

11. A shaker conveyer drive in accordance with 45 claim 8, in which the connection between the yoke and the reaction member includes a lever arm, and means for shifting the pivotal axis of said lever arm in such a manner as to reverse 50 the order of acceleration and deceleration of said driven crank without reversing its direction of rotation, and in which the pivotal axis of said lever arm is adjustable about an axis concentric with the axis of said reaction member.

12. In a shaker conveyer drive, a support including a frame member, a driving shaft, a driven shaft having a crank thereon, planetary drive gearing for rotating said crank with a predetermined variable angular velocity during each revolution thereof including a reaction member movable in opposite directions during each revolution of said crank, and means for reciprocably moving said reaction member in timed relation with said crank including a yoke guided for reciprocable translational movement in said frame member in one plane, a member guided in said yoke for reciprocable translational movement transversely of said yoke for reciprocably moving said yoke, and an operative connection between 70 said yoke and reaction member.

13. A shaker conveyer drive in accordance with claim 12, in which the member is journaled on said driven shaft eccentric of the center thereof.

14. A shaker conveyer drive in accordance with 75

claim 12, in which the connection between the yoke and the reaction member includes a lever arm, and means for shifting the pivotal axis of said lever arm in such a manner as to reverse the order of acceleration and deceleration of said driven crank without reversing its direction of rotation.

15. A shaker conveyer drive in accordance with claim 12, in which the connection between the yoke and the reaction member includes an annular projection encircling said driven shaft, a link journaled thereon, and a lever arm fulcrumed adjacent one of its ends, said lever arm being connected to said reaction member adjacent its opposite end, and to said link intermediate its ends.

16. A shaker conveyer drive in accordance with claim 12, in which the connection between the yoke and the reaction member includes an annular projection encircling said driven shaft, a link journaled thereon, and a lever arm fulcrumed adjacent one of its ends to an adjustable fulcrum member and connected to said reaction member adjacent its opposite end and said link intermediate its ends, and in which means are provided for shifting said fulcrum member in such a manner as to reverse the order of acceleration and deceleration of said driven crank without reversing its direction of rotation. 5 10

GLENN W. PACKER. 15
